UNITED STATES PATENT OFFICE.

ALBERT I. CRENSHAW, OF CHICAGO, ILLINOIS.

FLYING-MACHINE.

1,031,840.

Specification of Letters Patent.

Patented July 9, 1912.

Application filed March 25, 1911. Serial No. 616,850.

To all whom it may concern:

Be it known that I, ALBERT I. CRENSHAW, a citizen of the United States, residing at Chicago, in the county of Cook and State of Illinois, have invented new and useful Improvements in Flying-Machines, of which the following is a full, clear, concise, and exact description, reference being had to the accompanying drawing, forming a part of this specification.

My invention relates to improvements in flying machines, particularly of the type known as bi-planes. One of the objects of my invention is to provide an improved form of machine which may be readily controlled not only as to lateral balance but as to fore and aft balance.

I have shown for the purpose of disclosing my invention one embodiment thereof in the accompanying drawings, in which—

Figure 1 is a top plan view of my invention; Fig. 2 is a small view showing a plan of the bottom plane of my invention; Fig. 3 is a side elevation; Fig. 4 is a front elevation; Fig. 5 is a side view of the propeller used in connection with my flying machine; and, Fig. 6 is a front view of the propeller.

The structure shown in the drawings comprises a framework, over which is stretched an upper plane 2 and a lower plane 3. This framework preferably comprises the upper lateral spars 4 and 5, which are spaced apart at their ends by fore and aft struts 6 and 7 and are connected to similar bottom lateral spars by vertical corner posts 8, fore and aft struts 9 being provided for connecting the bottom lateral spars together. Connected to and extending longitudinally of the lateral struts are the upper longitudinal spars 10 and 11, which are spaced apart at their forward and rear ends by lateral spacers 12 and 13 and are connected to similar bottom spars 14 by vertical posts 15. The framework thus formed takes the shape in plan, in effect, of a pair of parallelograms, one extending laterally and the other overlapping the lateral parallelogram and extending transversely. Arranged on the struts 6 and 7, near the forward end of the machine, are two bell crank levers 16 and 17, which are suitably connected by a connecting rod 18 with a lever 19 pivoted to a suitable cross brace in the upper part of the frame. Extending forwardly from the spacer bar 13 is a third bell crank lever 20, which is connected by a connecting wire or rod 21 with a

foot lever 22 mounted in proximity to the driver's seat 23.

The upper plane may be formed of any suitable fabric, such as canvas or other material, and takes the general shape of a triangle having its base projected slightly and provided with a beak 24. The extreme lateral ends of the plane are connected to the ends of the bell crank levers 16 and 17. The edge of the plane is connected, as at 25 and 26, to the rear upper spar 4 of the framework and the rear end of the canvas is connected, as at 27, to the rear spacer 12. The front of the small beak 24 is connected to the end of the bell crank lever 20, while the side portions or inner ends of the beak are connected as at 27^a to the front spacer 13. It will thus be seen that the lateral edges or ends of the top plane form a pair of movable tips and the front beak 24 likewise forms a movable beak or tip in front of the machine. By operating the lever 19 one of the movable side tips may be depressed and at the same time the opposite tip will be elevated. Also, by operating the foot lever 22 the front beak or tip 24 may be depressed or raised.

Extending rearwardly from the framework above described is a framework comprising the upper and lower side spars 28 and 29 and the top and bottom spacer bars 30. The inner ends of the side spars are secured to the rear vertical posts 15 and vertical posts 31 extend between the rear ends of the upper and lower side spars 28 and 29. This fan tail frame is covered on all sides except its front and back by a suitable material, which may be the same as the top plane, and in effect forms a fan tail box 95 open at front and back. It will thus be seen that in top plan the upper plane, including the fan-tail box, resembles very closely the shape of a bird with its wings outspread.

The bottom plane, which may be formed of the same material as the top plane, conforms to the outline of the framework and has its front edge slightly rounded off and stiffened, as at 32.

Arranged in the front portion of the fan-tail box, on each side, is a pair of vertically arranged, rearwardly extending, angularly disposed planes 33, which are stationarily mounted, and pivoted between the top and bottom spacers 12 is a pair of vertically arranged movable planes 34 which may be moved so that their rear edges engage the

rear edges of the planes 33 and thereby completely close the box, or which may be adjusted in such position that a wide space is left between the planes 33. These planes 5 34 are provided with a pair of intermeshing segmental gears 34^a, so that the two planes will operate in synchronism, although in opposite directions, and the planes are operated by a connecting rod 35 attached at 10 its front end to a foot lever mechanism 36 arranged in juxtaposition to the driver's seat.

For steering the plane I provide a rudder 37, which is arranged in the front of the 15 machine above the bottom plane, and this rudder is provided with suitable operating mechanism 38 connected with an operating handle 39.

Extending between the vertical struts 20 connecting the rear upper and lower lateral spars is a propeller shaft 40 on which are mounted propellers 42 and 41. These propellers are of peculiar form and are preferably constructed in the form of tapering 25 helices, such as illustrated in Figs. 5 and 6, having their edges beveled as at 42, which edges during the rotation of the propellers tend to force the machine forward. Extending transversely of the larger portion 30 of the helices is a vertical blade 43 which also aids in propelling the machine forward.

The shaft 40 is driven from a suitable engine 44 by means of gear mechanism 45.

While I have shown and described the preferred embodiment of my invention in the accompanying drawings and specification, it will be understood that various modifications and changes may be made 40 therein without departing from the spirit of my invention as set forth in the accompanying drawings.

Having thus described my invention, what I claim as new and desire to secure by 45 Letters Patent, is:—

1. In a flying machine, the combination with a lower plane having lateral rectangular wings, a rearwardly extending rectangular tail-piece and a fan-shaped extension of 50 said tail-piece, and an upper plane substantially triangular in shape having a fan-tail extension from the apex of the triangle

and a triangular beak extending forwardly from the base of the triangle.

2. A flying machine comprising a lower 55 plane having transverse rectangular wings, a rearward rectangular extension from said wing, an upper plane substantially triangular in shape, and a box fan-tail open at its front and back connected at the apex 60 of the upper plane and to the rear of the rearward extension of the lower plane.

3. In a flying machine, the combination with an upper and lower frame forming a transversely extending parallelogram and a 65 rearwardly extending parallelogram, a covering for the bottom frame, conforming substantially to the shape thereof, and a suitable cover extending over the top frame, substantially triangular in shape, and having 70 its ends projecting beyond the sides of the frame and having a triangular beak extending beyond the front of the frame, and means for raising and lowering the ends and said beak.

4. In a flying machine, the combination with a lower plane having lateral rectangular wings and a rearwardly extending tail piece, a top plane substantially triangular in shape, a box fan-tail open at its front and 80 rear connected to the rear of said plane, and means for controlling the size of the opening in said box.

5. In a flying machine, the combination with a lower plane having lateral rectangular wings and a rearwardly extending tail piece, an upper plane substantially triangular in shape and a box fan-tail secured to the rear of said plane, angularly disposed planes arranged between the top and bottom of said 90 box fan-tail, a pair of planes pivoted at their center and so arranged that their rear edges will respectively engage the edges of said diagonally arranged planes and the front edges engage with one another, and means for moving said planes on their respective pivots to vary their position.

In witness whereof, I have hereunto subscribed my name in the presence of two witnesses.

ALBERT I. CRENSHAW.
